W. E. STANDLEY.

CUTTING OFF DEVICE FOR GLASS DRAWING APPARATUS.
APPLICATION FILED AUG. 20, 1915. RENEWED MAR. 13, 1920.

Patented Apr. 27, 1920.

UNITED STATES PATENT OFFICE.

WILLIAM E. STANLEY, OF PITTSBURGH, PENNSYLVANIA, ASSIGNOR TO WINDOW
GLASS ROTARY POT COMPANY, A CORPORATION OF PENNSYLVANIA.

CUTTING-OFF DEVICE FOR GLASS-DRAWING APPARATUS.

1,338,109.

Specification of Letters Patent. Patented Apr. 27, 1920.

Application filed August 20, 1915, Serial No. 46,442. Renewed March 13, 1920. Serial No. 365,825.

To all whom it may concern:

Be it known that I, WILLIAM E. STANLEY, a citizen of the United States, and a resident of Pittsburgh, in the county of Allegheny and State of Pennsylvania, have invented a new and useful Improvement in Cutting-Off Devices for Glass-Drawing Apparatus, of which the following is a specification.

10 This invention relates to cutting off devices for glass drawing apparatus, and particularly to devices for cutting off from the remaining material in the pot the glass cylinder drawn from the pot by the usual bait 15 drawing head. The object of the invention is to provide a simple form of cutting off device which is easily operated, which severs the glass along a regular line, and which is of a nature to coöperate with the bait in 20 cooling or chilling the glass for attaching it to the bait at the beginning of the drawing operation. A further object of the invention is to provide a device of this kind which can be manufactured at low cost and 25 which is protected from the heat of the furnace so that it is durable and is not liable to burn out in service. Further objects of the invention are in part obvious and in part will appear more in detail hereinafter.

30 In the drawings, Figure 1 is a sectional elevation through one form of glass furnace with the invention applied thereto; Fig. 2 is an enlarged detail section through the cutting off ring; and Fig. 3 is a plan view of 35 said ring, partly in section.

The furnace as shown in the drawings for purposes of illustration comprises a hearth 1 on which is located the pot 2, said furnace being heated by gas or in any other manner, as desired. Above the furnace is a frame 3 along which slides vertically a carriage 4 carrying the bait or drawing head 5 connected to a shaft 6 telescoping through a stuffing-box into a larger pipe 7 connected 40 to a source of compressed air 8. This structure is more fully described in the copending application filed by myself and Thomas B. Campbell for glass drawing and blowing apparatus, of even date herewith, Serial No. 46,441, and need not be further described, as it forms no part of the present invention.

After the glass cylinder is drawn from the pot by the bait in the usual manner, it is necessary to cut off the cylinder from any 55 glass remaining in the pot. For this pur-

pose I provide a ring 10 of a diameter large enough to completely surround the largest sized cylinder to be drawn in the apparatus. This ring has two walls, an inner wall 11 and an outer wall 12. The inner wall is 60 substantially triangular in cross section and may be made of any suitable material, such as brass, iron or the like. At one side it is provided with a boss 13, which is bored and tapped to receive two pipes 14 communicating with the passage or space 15 within the inner wall on either side of a partition 15^a therein. This ring with the pipes 14 attached thereto is placed in the mold for casting the outer wall 12, in the same manner as 70 the core is placed in said mold, so that in the casting operation the inner wall is cast into the outer wall, leaving the pipes 14 projecting through said outer wall. The outer wall is larger than the inner wall so as to leave 75 a space 16 between said walls, for a purpose to be described.

The pipes 14 form a connection for conducting a supply of gas to the space 15 within the inner wall and are therefore coupled 80 to a conduit (not shown) leading to a gas supply. This gas supply is directed against the outer surface of the glass cylinder for cutting off the same, and passes out from the space 15 through a series of suitable outlets 18 spaced at intervals around the inner surface of the ring and shown as formed of small nozzles or pipe members passing through openings in the outer ring and screwed into tapped openings in the inner 90 ring. At the conclusion of the drawing operation the gas supply is turned on, so that a circular sheet of flame is directed against the glass cylinder, which melts the same along a regular line and severs it from the 95 remaining glass in the pot.

The double walled construction of the cutting off ring protects it from the injurious effects of the high temperature, but it is preferably cooled by a water supply introduced to the hollow space 16 between the two walls 11 and 12. As shown, said space is divided at one point in its periphery by a cross wall or partition 19, and the water supply is conducted to one end of said space 100 through a conduit 20. The outlet from said space is at the other end of said space on the other side of the wall 19 through a conduit 22, so that the current of water flows entirely around the ring before it leaves it. 110

The ring is preferably supported from above so that it may be raised and lowered for purposes of adjustment and to allow manipulation of the pot or furnace. As shown, it is provided on opposite sides with upwardly extending rods 23 connected to cables 24 passing over a pulley to a winding drum, which may be operated by a hand wheel or in any other manner.

10 The ring lies in a position directly opposite the drawing head or bait 5, which is above the upper edge of the pot. It is of cast metal and is comparatively massive, so that it absorbs and conducts away the heat 15 of the glass clinging to the bait and thereby assists in chilling the same and attaching it to the bait.

It will be noted that the ring covers the edges of the glass pot and seals the openings 20 around the sides of the pot and also incloses the space in the furnace immediately above the glass pot. In furnaces of the character with which this improvement is used, the space or head room above the pot, when the 25 furnace is being operated, is filled with hot gases which, when a cylinder is drawn from the pot, will strike the cylinder and either break it or cause it to bulge, unless some means is employed to prevent the gases striking the cylinder. The ring 10, which constitutes a cooling and a cutting-off device, also serves the function of protecting the 30 glass cylinder against these gases. It is made of proper size to inclose the space between the glass pot over which it is positioned and the cap of the furnace and it further seals the gas passages around the outside of the glass pot. Consequently, when this ring is lowered to position, it prevents 35 the hot gases from striking the cylinder of glass that is being drawn and thereby prevents the gases from striking and destroying the cylinder.

The glass cylinders which are drawn with 40 a machine of this kind are often 30 feet long and the amount of glass will weigh 250 pounds. If the cylinder is broken in some way by the action of gases striking it so that it falls back into the glass pot, the glass 45 will strike the edge of the pot and break it to pieces. This not only causes a loss of the glass pot but stops the machine and requires a cleaning out of the glass which is scattered throughout it. When the cooling 50 and cutting-off device herein disclosed is used, however, it covers the edge of the glass pot, and in the event that a cylinder should fall it cannot strike the edge of the pot but hits the molten glass body in the pot and is 55 cushioned to such an extent that the pot is not broken. These two functions of the ring are very important and contribute very materially to the success of the machine.

The device thus has four functions, it 60 cools the glass in a drawing bait, it may be

used to cut off the glass cylinder, it protects the glass pot and it prevents the gases from striking the glass cylinder which is being drawn.

What I claim is:—

1. A cooling and cutting off device for 70 glass cylinders, comprising an annular casting provided in its body with an annular gas conduit and a passage to receive a cooling medium to cool the glass that attaches to a drawing bait, said gas conduit being arranged to be attached to a gas supply and having a plurality of outlets for directing a series of gas jets against the periphery of the glass cylinder. 75

2. A cooling and cutting off device for 80 glass cylinders, comprising an annular casting provided in its body with an annular gas conduit and with a chamber surrounding said conduit and arranged to receive a cooling medium to cool the glass that attaches to a drawing bait, said gas conduit being arranged to be attached to a gas supply and having a plurality of outlets for directing a series of gas jets against the periphery of the glass cylinder. 85

3. Apparatus for cutting off glass cylinders, comprising an annular conduit provided with connections to a gas supply, a series of outlets from said conduit arranged 95 to direct jets upon the periphery of the glass cylinder, and a water jacket surrounding said conduit for cooling the same.

4. Apparatus for cutting off glass cylinders, comprising an annular conduit provided with connections to a gas supply, a series of inwardly extending nozzles spaced at intervals around said conduit for directing gas jets upon the periphery of the glass cylinder, and a water jacket surrounding 100 said conduit for cooling the same. 105

5. Apparatus for cutting off glass cylinders, comprising a double walled ring, means for supplying gas to the space within the inner wall of said ring, and a series of 110 outlets from said space for directing gas jets upon the periphery of the glass cylinder.

6. Apparatus for cutting off glass cylinders, comprising a double walled ring, 115 means for supplying gas to the space within the inner wall of said ring, a series of outlets from said space for directing gas jets upon the periphery of the glass cylinder, and means for circulating a cooling medium 120 through the space between said walls.

7. Apparatus for cutting off glass cylinders, comprising a double walled ring, means for supplying gas to the space within the inner wall of said ring, and a series of 125 nozzles communicating with the space within the inner wall and extending through said outer wall for directing gas jets upon the periphery of the glass cylinder.

8. Apparatus for cutting off glass cylin- 130

ders, comprising a double walled ring, means for supplying gas to the space within the inner wall of said ring, a series of nozzles communicating with the space within 5 the inner wall and extending through said outer wall for directing gas jets upon the periphery of the glass cylinder, and means for circulating a cooling medium through

the space between the two walls of said ring.

In testimony whereof I have hereunto set my hand.

WILLIAM E. STANDLEY.
